LIQUID DISPENSING APPARATUS

Henry Shapiro, Philadelphia, Pa., assignor of one-half to Samuel J. Becker, Philadelphia, Pa.

Application November 23, 1935, Serial No. 51,337

14 Claims. (Cl. 128—214)

This invention relates to liquid dispensing apparatus, and more particularly to apparatus for dispensing aseptic medicinal fluids without danger of contaminating the same.

5 The practice of injecting fluids intravenously, intramuscularly, subcutaneously, etc. into animal tissue is well known to medical science. In accordance with accepted practice, the aseptic medicinal liquid is usually withdrawn from a bulk 10 container by means of a hypodermic syringe with which the liquid is injected into the patient. The removed liquid must be replaced by air which, in most cases, comes into contact with the remaining liquid directly from the atmosphere, and 15 in some cases even passes through the liquid to the air space thereabove.

It is well known, of course, that atmospheric air contains various forms of bacteria, mold 20 spores, dust, and other impurities which will necessarily contaminate the remaining liquid in the container with which the air comes in contact, thus rendering the liquid septic and unfit for injection purposes. Various proposals have been 25 made to prevent the air from contaminating the liquid, such as passing the air through a wad of cotton or other absorbent material saturated with a sterilizing solution prior to admitting it into the container. However, the systems incorporating such proposals and with which I am familiar 30 all have numerous objections thereto. For example, in the case of a wad of cotton saturated with a sterilizing solution, the path through the wad of cotton is usually so short that it is by no means certain that all the impurities will be removed from the air. Moreover, in the example 35 given, it not infrequently happens that the sterilizing solution evaporates to a point where the wad of cotton becomes ineffective for the purpose intended unless it is again saturated or 40 replaced with a new, saturated wad.

The primary object of my invention is to provide an improved method of and means for insuring sterilization of the air prior to its entry into the air space in the container whereby the 45 danger of contaminating the aseptic medicinal liquid is eliminated.

More specifically, it is an object of my invention to provide an improved liquid dispensing apparatus which will effectively wash the atmospheric air to render it free from foreign matter and which will, at the same time, sterilize the air to render it fit for admission into the container.

Another object of my invention is to provide 50 improved means for storing and shipping an

aseptic medicinal liquid without subjecting the liquid to the danger of contamination from the atmosphere.

Still another object of my invention is to provide improved means, in apparatus of the type 5 aforesaid, for permitting the withdrawal of the liquid at any desired rate adjustable within predetermined limits.

A further object of my invention is to provide improved liquid dispensing apparatus wherein 10 the air, although admitted from a point below the liquid, does not pass through the liquid itself in order to reach the air space thereabove.

It is also an object of my invention to provide improved liquid dispensing apparatus as afore- 15 said which is simple and practical in construction, which provides adequate insurance for the liquid in the container against contamination, which is inexpensive to manufacture, which can be manipulated with great facility, and which is 20 very efficient in operation.

In accordance with my invention, I store the aseptic medicinal liquid in a previously sterilized container which I close with a stopper member having an inwardly directed portion extending 25 into the liquid, the stopper, of course, also having been previously sterilized. The stopper may then be sealed to the container, if desired, although this is not absolutely necessary. When so put up in bulk, the liquid may be stored and 30 shipped with the knowledge that it can only become contaminated and made septic by removing the stopper and admitting contaminated material into the container. The inwardly directed portion of the stopper member is filled with a 35 sterilizing medium when the liquid is ready for withdrawal from the container, and a venting device is inserted thereinto through which the air is admitted from the atmosphere and through which the air preferably is made to pass in a 40 relatively long, circuitous path, the air passing therefrom through the sterilizing medium and thence into the air space within the container above the liquid. The venting device is provided with means for regulating the rate of flow of air 45 therethrough whereby the rate at which the liquid is withdrawn from the container is also regulated.

The novel features that I consider characteristic of my invention are set forth with particularity in the appended claims. The invention itself, however, and its method of operation, together with additional objects and advantages thereof, will best be understood from the following description of several embodiments thereof 50 55

when read in connection with the accompanying drawings in which—

Figure 1 is a sectional view of a container filled with liquid and stoppered for storage in accordance with my invention.

Figure 2 is a similar view showing the container in inverted, operative position with the air venting device of my invention inserted preliminary to adjustment thereof in operating position.

10 Figure 3 is a view similar to Figure 2 but showing the air venting device in operating position.

Figure 4 is a sectional view taken on the line IV—IV of Figure 2.

Figure 5 is a sectional view of a modified form 15 of air venting device constructed in accordance with my invention,

Figure 6 is a sectional view of still another modification of an air venting device formed in accordance with my invention,

20 Figure 7 is a sectional view of a modified form of container according to my invention, and

Figure 8 is a sectional view of a modified form of stopper device for the container.

Referring more specifically to the drawings, 25 wherein similar reference characters designate corresponding parts throughout, there is shown, in Figures 1, 2 and 3, a container 1 comprising a receptacle for receiving an aseptic medicinal liquid 3 and having a normally open neck portion 5 which is externally threaded. Tightly fitted 30 into the neck 5 is a rubber, cork, or other suitable stopper 7 having a substantially central opening 9 therein and at least one other opening 11 radially spaced from the opening 9. Within the opening 9 is tightly fitted a tubular member 13 of glass or 35 any other suitable material, the member 13 being formed with a somewhat inturned or reduced end portion 15 apertured at 17, and a soft rubber plug or closure member 19 normally closing the aperture 17. Except for the opening 11, therefore, the 40 stopper 7, tube 13 and closure 19 constitute means for shutting off the contents of the container 1 from the atmosphere, and a rubber or similar disc 21 is placed over the stopper 5 to cover the opening 11, as shown in Figure 1, whereby to completely 45 shut off the liquid 3 from the atmosphere. A metallic disc 23 is placed over the rubber disc 21 and is held in place by a cap member 25 threaded on the neck 5. The bottle or receptacle 1 is sterilized prior to the introduction of the aseptic 50 liquid 3 therein, as are also the stopper 5, the tube 13, the closure member 19 and the disc 21. Thus, when the cap 25 is applied (and, if desired, sealed 55 to the container 1), the liquid 3 is effectively sealed against contamination and the container 1 is ready for shipment and storage until ready for use, the container 1 being maintained in upright 60 position while stored.

The tubular member 13 is provided to receive 65 an air venting device generally designated by the numeral 27 by means of which atmospheric air may be admitted into the container 1 for withdrawal of the liquid 3 therefrom, and also to receive a sterilizing medium 28 for sterilizing and cleaning the air prior to its entry into the air 70 space above the liquid 3. The form of my improved venting means shown in Figures 2 and 3 comprises an outer sleeve or tube 29 of an external diameter materially less than the internal diameter of the tubular member 13, an inner 75 sleeve or tube 31 spaced from the tube 29 by a spacing sleeve 33 which extends from a disc-like member 35, and a central rod-like member 37 threaded into a block 39 which is force fitted into or otherwise suitably secured in the upper end of the tube 29, the tubes 13, 29 and 31 and

the rod 37 being, preferably, arranged concentrically to each other. Threaded on the reduced extension 41 of the block 39 is a pointed member 43 adapted to pierce the soft rubber closure 19 when forced thereagainst and having a small air 5 chamber 45 therein. The member 43 is also provided with one or more vents 47 which provide communication between the interior of the tube 13 and the chamber 45, and with a passage or duct 48 terminating adjacent its tip and also 10 communicating with the chamber 45. Thus, when the tip of the member 43 is forced through the closure or plug 19 at least to the extent shown in Figure 3, communication is established between the interior of the tubular member 13 and the 15 interior of the container 1 via the vents 47, the chamber 45 and the duct 48.

For manipulating the closure piercing member 43, I provide a cylindrical manipulating cap 51 having a centrally disposed bolt 53 which is 20 adapted to cooperate with the threaded bore 38 at the lower end of the rod 37, the cap 51 being formed with a peripheral flange 55 which is held against the lower face of the disc-like member 35 by a plurality of pins 57 in the cap member 25. 25 Depending from the disc-like member 35 within the cap 51 is a diametrically slotted and centrally bored boss 59 the bore of which is of a diameter sufficient to receive a terminal member 61 force fitted onto or otherwise suitably secured to the rod 37 and having a pair of diametrically opposed extensions 63 received within the diametrical slot of the boss 59 for preventing rotation of the rod 37. Now, as the manipulating cap 51 is rotated, the rotation of the bolt 53 will 30 cause the rod 37 to be raised or lowered, depending upon the direction of rotation of the cap 51, the block 39, the closure piercing member 43 and the tube 29 being simultaneously raised or lowered, as the case may be.

When it is desired to withdraw a portion of the 40 medicinal liquid 3 from the container or receptacle 1, the cap 25 and the discs 21 and 23 are first removed and the sterilizing solution 28 (for example, alcohol) is poured into the tube 13 to 45 partially fill the same. Although this leaves the opening 11 temporarily open, the atmospheric air will not enter into the receptacle 1 there-through because the space above the liquid 3 (including the opening 11) is already filled with sterilized air. A rubber or similar washer 65, 50 previously sterilized, is then placed over the rim of the tube 13 after which the venting unit 27, also previously sterilized, is inserted into the tube 13 and adjusted so that the aperture 36 in the disc-like member 35 is aligned with the opening 55 11 in the stopper 7. Thereupon, the cap 25 is screwed onto the neck 5 until the pins 57 engage and hold the flange 55 against the member 35, a previously sterilized discharge tube 67 provided, if desired, with a stopcock 69 is inserted into the opening 11 through the aperture 36, and the container 1 is inverted to the position shown in Figure 2 and placed upon or suspended from a suitable support (not shown).

With the stopcock 69 open, the cap 51 is then 65 manipulated in a clockwise direction until the member 43 has been raised sufficiently to pierce and extend through the soft rubber closure 19 as shown in Figure 3, the rod 37 and the tube 29 having been, of course, simultaneously raised longitudinally with respect to the tube 31. Air leaking 70 in between the flange 55 and the disc-like member 35 then passes through the diametrical slot in boss 59 past the terminal member 61 and in a circuitous path around the rod 37 and the tubes 75

31 and 29 to the vents 47. The air first passes upwardly in the space between the rod 37 and the tube 31, reverses itself around the upper end of the tube 31 and passes downwardly between the tubes 31 and 29, thence through one or more apertures 71 in the lower end of the tube 29, up again in the space between the tubes 29 and 13 and through the solution 28 which thoroughly cleans and sterilizes it, through the vents 47 into the chamber 45 which, if desired, may be filled with a wad of cotton saturated with the same or another sterilizing solution, and finally through the duct 49 into the air space above the liquid 3. Thus, the air coming from the atmosphere is rendered clean and sterile prior to reaching the interior of the receptacle 1.

The rate at which the liquid 3 is discharged from the container 1 may be controlled in several ways. If desired, the stopcock 69 may be initially adjusted for this purpose. As the cap 51 is manipulated and the tube 29 moved with respect to the spacing sleeve 33, it is evident that the extent of overlap between the sleeve 33 and the apertures 71 will vary. The position and size of the apertures 71 as well as the length of the sleeve 33 may be so chosen, therefore, that the flow of air through the apertures 71 will be controlled by manipulating the cap 51. It is also possible to obtain some measure of control dependent upon the extent to which the terminal end of the duct 49 is shut off by the closure 19. In any event, it will be obvious that the flow of liquid from the container 1 can be adjusted very critically and can be entirely stopped by merely turning the cap 51 counterclockwise until the member 43 is withdrawn from the closure 19.

The modification of my improved venting device or unit shown in Figure 5 is similar to that shown in Figures 2 and 3. In this modification, however, the tube 29 has a tapered extension 73 which forms the chamber 45 and has the vents 47 therein, while the closure piercing member is constituted by a pointed extension 75 on the rod 37, the extension 75 being provided with a Y-shaped duct 77 therein corresponding to the duct 49 and serving to establish communication between the chamber 45 and the interior of the container 1. A collar 79 on the rod 37 is adapted to cooperate with a flange 81 on the tube 29 to prevent the air from passing up in the space between the rod 37 and tube 31 without first passing through the sterilizing solution 28.

In Figure 6, I have shown a further and somewhat simplified form of venting device 27 wherein in the rod 37 and the boss 59 are eliminated. The tube 31 in this modification extends through an externally threaded sleeve 83 upon which is threaded the outer tube 29. The tube 13 is fitted over a rubber stopper 85 fitted within the cap 51, while the tube 31 is fitted within the central bore 87 in the stopper 85, the closure piercing member 43 being force fitted into the tube 29. Preferably, the manipulating cap 51 is provided with a threaded opening through which access may be had to the interior of the tube 31, a suitable covering cap 89 closing this opening but permitting the leakage of air into the tube 31. By properly turning the manipulating cap 51, the tube 29 is raised to cause the member 43 to pierce the closure 19 as in the two modifications previously described, and the air from the atmosphere passes up through the tube 31, thence down between the tubes 31 and 29, and subsequently up through the sterilizing solution

28, the vents 47, the chamber 45 and the duct 49 into the container 1.

Figure 7 shows a modified bottle or container formed in accordance with my invention and wherein the inwardly extending tubular member 5 13 is made integral with the container 1. This eliminates the necessity for the stopper 5. A hollow nipple 91 extending from the container 1 and suitably stoppered with a sterilized stopper during storage may be used for connecting 10 the discharge tube 67 when the liquid 3 is to be withdrawn from the container.

In Figure 8, there is shown a modified form of stopper device for the container by means of which the possibility of entrance of atmospheric air into the container 1 is entirely eliminated. In this form of my invention, the stopper 7 is provided with a cut-away portion 7a adjacent its lower surface and with a hemispherical seat or depression 7b in its upper surface. The opening 11 extends from the depression 7b through the stopper 7 to its lower surface, while a second opening 93 extends from the depression 7b to the cut-away portion 7a, communicating with the opening 11 adjacent its upper end. From an inspection of Figure 8, it will be seen that the opening 93 is considerably shorter than the opening 11. Fitted into the opening 11 is a tube 95 which is sealed at both its ends and is provided with an opening 97 near its lower end and 30 a reduced neck 98 adjacent its upper end which terminates in a somewhat spherical element 99 which may easily be grasped by the fingers. When the container 1 is originally stoppered, the tube 95 is in the position shown in Figure 8 with 35 the opening 97 within the stopper opening 11. The tube 95 also blocks off entrance to the opening 93. Thus, there is no possibility of entrance of atmospheric air to contaminate the contents of the container 1. When the container 1 is 40 to be set up for use in the manner heretofore described, the tube 95 is withdrawn only sufficiently to have its lower end barely pass the upper end of the opening 93, whereupon the tube 95 is inserted into the opening 93 a distance sufficient to bring the opening 97 into the cut-away portion 7a. This enables the liquid 3 to pass into the opening 97 and through the tube 95 when the container 1 is inverted. By breaking off the portion 99 at this time, communication is established between the inside of the container and the outside for dispensing the medicinal liquid 3. It will be noted that, inasmuch as the tube 95 always shuts off the common entrance to the openings 11 and 93 from the depression 7b, there 55 is no possibility of entrance of atmospheric air into the container 1.

From the foregoing description, it will be apparent to those skilled in the art that I have provided a liquid dispensing device which will 60 insure the liquid against being contaminated by atmospheric air, and, although I have shown and described several embodiments of my invention, I am fully aware that many other modifications thereof and changes therein may be made without departing from the spirit thereof. For example, if desired, the washer 65 may be entirely dispensed with, although I prefer to use this washer to provide a seal between the tubular member 13 and the disc-like member 35. Also, 70 in place of a solid disc 21 and solid disc 23, they may be in the form of annuli placed on the stopper 5 so as to cover only the opening 11, it being immaterial whether the tubular member 13 is also covered or not, since the closure mem- 75

ber 19 prevents entry of contaminating material to the liquid 3 through the tube 13. Moreover, to prevent the sterilizing solution 28 from passing into the container 1 through the vents 41, the chamber 45 and the duct 49 upon inversion of the container to upright position after the venting device 27 has been adjusted to the position shown in Figure 3, the bolt 53 may be extended through the base of the manipulating cap 51 and provided with a terminal member similar to the member 61 and arranged to cooperate with a second boss 59 and cap 51, a coiled spring being placed about the extension of the bolt 53 between its terminal member and the cap 51 shown, for example, in Figure 3. Thus, when the second cap (not shown) is released, the spring will automatically withdraw the member 43 from the closure 19 and permit the closure 19 to seal itself, whereby the sterilizing solution is prevented from entering into the container 1. Many other changes and modifications will, no doubt, readily suggest themselves to those skilled in the art. I desire, therefore, that my invention shall not be limited except insofar as is necessary by reason of the prior art and the spirit of the appended claims.

I claim as my invention:

1. In liquid dispensing apparatus, the combination of a container, a tubular member extending thereto, venting means within said tubular member for establishing communication between the atmosphere and the interior of said container, and air sterilizing means within said tubular member, said venting means being so constructed and so arranged within said tubular member as to cause the air to pass through said sterilizing means prior to entering into said container.

2. In liquid dispensing apparatus, the combination of a container, a tubular member extending thereto, venting means within said tubular member for establishing communication between the atmosphere and the inside of said container, said venting means being spaced from said tubular member, and air sterilizing means within the space between said tubular member and said venting means, said venting means being arranged to direct the air through said sterilizing means prior to directing the air into said container.

3. In liquid dispensing apparatus, the combination of a container having a neck portion, a stopper fitted into said neck portion and including a tubular member extending into said container, said tubular member having a normally open inner end, a closure for said end, venting means within said tubular member in spaced relation thereto, said venting means extending through said closure for establishing communication between the atmosphere and the interior of said container, and air sterilizing means within the space between said venting means and said tubular member, said venting means having communication with said space adjacent said neck whereby the air admitted by said venting means from said atmosphere is caused to pass through said sterilizing means prior to entry into said container.

4. The invention set forth in claim 3, characterized in that said closure comprises a pierceable member and characterized further in that said venting means includes a member adapted to pierce said closure, said piercing member having an air duct therein in communication with the space containing the sterilizing means and

adapted to communicate with the interior of said container.

5. The invention set forth in claim 3 characterized in that said closure comprises a pierceable member, characterized further in that said venting means includes a member adapted to pierce said closure and having an air duct therein in communication with the space containing the sterilizing means, and characterized still further by the addition of means for causing said piercing member to pierce said pierceable member whereby to establish communication between the space containing said sterilizing means and the interior of said container.

6. In liquid dispensing apparatus, the combination of a container, a tubular member extending thereto, and venting means within said tubular member for establishing communication between the atmosphere and the interior of said container, said venting means comprising a plurality of spaced, concentric members providing a circuitous path therebetween for the air.

7. In liquid dispensing apparatus, the combination of a container, a tubular member extending thereto, and venting means within said tubular member for establishing communication between the atmosphere and the interior of said container, said venting means comprising a plurality of spaced, concentric, relatively adjustable members providing a circuitous path therebetween for the air.

8. In liquid dispensing apparatus, the combination of a container, a tubular member extending thereto, and venting means within said tubular member for establishing communication between the atmosphere and the interior of said container, said venting means comprising a plurality of spaced, concentric members adjustable relative to each other in a longitudinal direction and providing a series of reversely directed successive passages for the air.

9. In liquid dispensing apparatus, the combination of a container, a tubular member extending thereto and having a normally open inner end, a pierceable closure for said end, venting means within said tubular member for establishing communication between the atmosphere and the interior of said container, said venting means comprising a plurality of spaced, concentric members adjustable relative to each other in a longitudinal direction and including a closure piercing device on one of said members, and means for adjusting said members to bring said piercing device into piercing relation with said closure.

10. In liquid dispensing apparatus, the combination of a container, a tubular member extending thereto and having a normally open inner end, a pierceable closure for said end, venting means within said tubular member in spaced relation thereto for establishing communication between the atmosphere and the interior of said container, said venting means comprising a plurality of spaced, concentric members adjustable relative to each other in a longitudinal direction and including a pointed closure piercing device on one of said members, said members providing a series of reversely directed successive passages for the air, the outermost of said passages having communication with the space between said venting means and said tubular member, and said closure piercing device having a duct therein terminating adjacent the point of said piercing device and also communicating with said space, and means for longitudinally ad-

justing said members to cause said piercing device to pierce said closure whereby communication may be established between said duct and the interior of said container.

5 11. The invention set forth in claim 10 characterized by the addition of air sterilizing means in the space between the venting means and the tubular member for sterilizing the air as it passes through said venting means from the atmosphere 10 to the interior of the container.

12. The invention set forth in claim 10 characterized in that the container is provided with an outlet adjacent said tubular member for withdrawal of the liquid therefrom.

15 13. In combination, a container adapted to receive a liquid and having a normally open neck, a stopper for said neck, said stopper being provided with a plurality of openings and with a depression in its outer surface, said openings 20 all communicating with the interior of said container and at least two of said openings being angularly related and intercommunicating with each other adjacent said depression, and a tube

fitted into one of said two intercommunicating openings and blocking entrance to the other of said two intercommunicating openings, said tube having an aperture therein adjacent its inner end but within said one opening and including a head portion within said depression for facile grasping and removal thereof from said one opening and insertion into said other opening.

14. In liquid dispensing apparatus, the combination of a container, a normally open-ended tube extending into said container, pierceable means closing one end of said tube, venting means within said tube for establishing communication between the atmosphere and the interior of said container, said venting means including a member adapted to pierce said pierceable means, and means for manipulating said venting means to either bring said piercing member into or withdraw said member from piercing relation with said pierceable means.
